(57) **CLAIM**

The ornamental design for a toilet brush set, as shown and described.

DESCRIPTION

FIG. 1 is a top, front perspective view of a first element of a toilet brush set, showing my new design;

FIG. 2 is a bottom, rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top, front perspective view of a second element of a toilet brush set, showing my new design;

FIG. 10 is a bottom, rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a top, front perspective view of a third element of a toilet brush set, showing my new design;

FIG. 18 is a bottom, rear perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

FIG. 25 is a top, front perspective view showing the three elements in a composite state; and,

FIG. 26 is a bottom, rear perspective view thereof.

The broken lines in the drawings illustrate the portions of the toilet brush set, which form no part of the claimed design.
